NURSE'S SURGICAL CAP

Harold Zimmon, Los Altos Hills, and Dee L. Strom, Sunnyvale, Calif., assignors, by mesne assignments, to American Hospital Supply Corporation, Evanston, Ill., a corporation of Illinois

Filed July 31, 1967, Ser. No. 8,072

Term of patent 14 years

Int. Cl. D2—03

U.S. Cl. D2—243

FIG. 1.

FIG. 2.

FIG. 3.

FIG. 4.

FIG. 1 is a front perspective view of a nurse's surgical cap showing my new design, the broken line indication of a wearer being for purposes of illustration only;

FIG. 2 is a rear perspective view thereof;

FIG. 3 is a front perspective view of the cap shown in FIG. 1 in an untied position; and

FIG. 4 is a plan view thereof in flat condition with the ties extended.

FIG. 5 is a bottom plan view of said cap.

We claim:

The ornamental design for nurse's surgical cap, as shown and described.
